US0D1001122S

(12) **United States Design Patent** (10) **Patent No.:** **US D1,001,122 S**
(45) **Date of Patent:** **** Oct. 10, 2023**

(54) **MOBILE COMPUTING DEVICE**

(71) Applicant: **ZEBRA TECHNOLOGIES CORPORATION**, Lincolnshire, IL (US)

(72) Inventors: **David William Reber**, Cedar Park, TX (US); **Kevin M. Bosse**, Cedar Park, TX (US)

(73) Assignee: **Zebra Technologies Corporation**, Lincolnshire, IL (US)

(**) Term: **15 Years**

(21) Appl. No.: **29/694,197**

(22) Filed: **Jun. 7, 2019**

(51) **LOC (14) Cl. 14-02**

(52) **U.S. Cl. D14/341**
USPC ....

CLAIM

The ornamental design for a mobile computing device as shown and described.

DESCRIPTION

FIG. 1 is a front perspective view of a mobile computing device;

FIG. 2 is a rear perspective view thereof;

FIG. 3 a front view thereof;

FIG. 4 is a rear view thereof;

FIG. 5 is a top view thereof;

FIG. 6 is a bottom view thereof;

FIG. 7 is a first side view thereof; and

FIG. 8 is a second side view thereof.

The broken lines shown in FIGS. 1-8 illustrate portions of the mobile computing device that form no part of the claimed design.

1 Claim, 6 Drawing Sheets
